UNITED STATES PATENT OFFICE.

EDWARD J. DAIGLE, OF SHERIDAN, WYOMING.

DESIGN FOR A BOX OR SIMILAR RECEPTACLE FOR CANDY.

Application filed August 1, 1927. Serial No. 22,970. Term of patent 7 years.

To all whom it may concern:

Be it known that I, EDWARD J. DAIGLE, a citizen of the United States, residing at the city of Sheridan, in the county of Sheridan and State of Wyoming, have invented a new, original, and ornamental Design for Box or Similar Receptacle for Candy, of which the following is a specification, reference being had to the accompanying drawing, forming a part thereof.

The figure is a perspective view of a box or similar receptacle for candy showing the new design.

I claim:

The ornamental design for a box or similar receptacle for candy, as shown.

EDWARD J. DAIGLE.
